UNITED STATES PATENT OFFICE.

CARROLL A. EDMONSTON, OF WASHINGTON, DISTRICT OF COLUMBIA.

DESIGN FOR A HANDLE FOR SPOONS OR SIMILAR ARTICLES.

No. 38,745.

Specification for Design.

Patented Aug. 6, 1907.

Application filed May 29, 1907. Serial No. 376,455. Term of patent 3½ years.

To all whom it may concern:

Be it known that I, CARROLL A. EDMONSTON, a citizen of the United States, residing at Washington, District of Columbia, have invented a new, original, and ornamental Design for the Handle of Spoons or Similar Articles, of which the following is a specification, reference being had to the accompanying drawing, forming part hereof.

In the drawing, Figure 1 is a front view showing my design and Fig. 2 is a rear view of the same.

I claim:

The ornamental design for the handle of a spoon, or similar article, as shown.

CARROLL A. EDMONSTON.
